DESIGN FOR A BELT GUARD FOR SEWING MACHINES

Max Ingwer, Forest Hills, Long Island, N. Y., assignor to Consolidated Sewing Machine & Supply Co. Inc., New York, N. Y., a corporation of New York

Application September 8, 1939, Serial No. 87,094

Term of patent 14 years

To all whom it may concern:

Be it known that I, Max Ingwer, a citizen of Austria, have taken out first papers to become a citizen of the United States, residing at Forest Hills, Long Island, county of Queens and State of New York, have invented a new, original, and ornamental Design for a Belt Guard for Sewing Machines, of which the following is a specification, reference being had to the accompanying drawing, forming part thereof.

Figs. 1 and 2 are perspective views of a belt guard embodying the design as it appears on opposite sides of the same.

I claim:

The ornamental design for a belt guard for sewing machines, substantially as shown.

MAX INGWER.
